UNITED STATES PATENT OFFICE.

JOHN T. DEMPSTER, OF SUMMIT, NEW JERSEY, ASSIGNOR TO BERGMANN & COMPANY, OF NEW YORK, N. Y.

ELECTRIC-LAMP SOCKET.

SPECIFICATION forming part of Letters Patent No. 443,746, dated December 30, 1890.

Application filed May 24, 1890. Serial No. 362,989. (No model.)

To all whom it may concern:

Be it known that I, JOHN T. DEMPSTER, a subject of the Queen of Great Britain, residing at Summit, in the county of Union and State of New Jersey, have invented a new and useful Improvement in Electric-Lamp Sockets, of which the following is a specification.

My improvement relates to sockets employed with incandescent electric lamps.

10 The invention consists in improved circuit-connections for the socket, and in certain features of construction which will be hereinafter fully described and claimed.

15 In the accompanying drawings, which illustrate the invention, Figure 1 shows a side view of a lamp, and below the lamp a cross-section of the socket, the two parts of the socket being separated. Fig. 2 shows a side elevation of the socket, the two parts of the 20 socket being separated. Fig. 3 shows a side view of the lower part of the socket at right angles to the view in Fig. 2, and Fig. 4 is a plan view of the socket.

25 The upper section of the socket consists of three parts—the outer metal shell or sleeve 1, provided at its lower end with a screw-thread or other fastening means 2, and preferably provided at its top with a bead 3. Within this shell is an insulating-lining 4, preferably 30 of vulcanized fiber. Within this layer of insulation is a second metal-sleeve 5, extending partially through the outer sleeves and terminating at the bottom in a flange 6. In manufacturing this part of the socket a sheet of metal is rolled onto a sheet of the fiber, the 35 screw-thread being impressed on both sheets. They are then bent into cylindrical shape and inserted into the outer tube, and are properly cemented in place.

40 The lower section of the socket consists of a cup-shaped cap 7, having the screw-threaded flange 8 and the extension 9 for connection with a light fixture or bracket. Within the cap is supported an insulating-block, preferably of vulcanized fiber. This block in its preferred form is cylindrical at its base, with a segment cut away at 10. The block may be held in place by screws passing through the bottom of the cap. On the side of the block 45 which has been cut away are supported two

metal contact-pieces 11 12, secured in place by screws or otherwise. These pieces are bent to extend over the top of the insulating-block, as clearly shown in Figs. 3 and 4. The ends of the springs are preferably, though not necessarily, left a little above the face of the block, so that they may act as springs when the parts are in use.

The wires from the lighting-circuit pass through extensions 9. One wire is connected 60 to contact 11 and the other to contact 12. When the two sections of the socket are put together, flange 6 will bear on the spring end of contact 11, and contact 12 will occupy a portion of the central space within the flange. When 65 the lamp is screwed into its socket, the metal sleeve 13 on the lamp-base will make intimate contact with the sleeve 5, which, as we have just seen, bears on contact 11. The central terminal 14 of the lamp will bear on the other 70 contact 12, thus completing the circuit from the line through the filament of the lamp.

Instead of connecting the upper and lower sections of the socket by means of the screw-connection shown, it is evident that a bayonet-75 joint connection or other suitable locking means may be employed.

In the construction above described the parts are very simple and of such construction that they cannot well get out of adjustment, 80 and there is no electrical connection between the exposed portion of the socket and the screw-threaded sleeve into which the lamp-base, which is connected with the filament, is screwed. The circuit is complete independent 85 of the outer sleeve.

Having thus described my invention, what I claim is—

1. The combination, in an electric-lamp socket, of a metal sleeve, a second metal sleeve 90 within the same and insulated therefrom, terminating in a flange, an insulating-block insertible into the outer sleeve and carrying a contact co-operating with the flange, and a second contact, substantially as described. 95

2. The combination, in an electric-lamp socket, of a metal sleeve with insulating lining, a central metal sleeve shorter than the first and terminating in a flange, an insulating-block insertible into the outer sleeve and 100

carrying a spring-contact which bears against said flange, and a central spring-contact, substantially as described.

3. The combination, in an electric-lamp socket, of a metal sleeve, a second metal sleeve within the same and insulated therefrom, terminating in a flange, an insulating-block insertible into the outer sleeve and carrying a contact co-operating with the flange, a second contact, and means for locking the block in place, substantially as described.

4. The combination, in an electric-lamp socket, of a metal sleeve, a second metal sleeve

within the same and insulated therefrom, terminating in a flange, an insulating-block insertible into the outer sleeve and carrying a contact co-operating with the flange, a second contact, said block being supported in a cap, and means for locking the cap to the sleeve, substantially as described.

This specification signed and witnessed this 18th day of April, 1890.

JOHN T. DEMPSTER.
